DESIGN FOR A TOY FOOD MIXER

Carl H. Muller, St. Louis, Mo.

Application November 8, 1946, Serial No. 134,631

Term of patent 7 years

(Cl. D34—15)

To all whom it may concern:

Be it known that I, Carl H. Muller, a citizen of the United States, residing in St. Louis County and State of Missouri, have invented a new, original, and ornamental Design for a Toy Food Mixer, of which the following is a specification, reference being had to the accompanying drawing, forming a part thereof.

In the drawing:

Fig. 1 is a top plan view of a toy food mixer, showing my new design;

Fig. 2 is a side elevational view thereof;

Fig. 3 is a rear elevational view thereof, and

Fig. 4 is an elevational view showing the opposite side of the head portion.

I claim:

The ornamental design for a toy food mixer, substantially as shown.

CARL H. MULLER.
